CLAIM

The ornamental design for an medical instrument grip, as shown and described.

DESCRIPTION

FIG. 1 is a top, front, left perspective view of a medical instrument grip in accordance with my design, shown in an environment;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines shown form no part of the claimed design.
